US00D488819S

(12) **United States Design Patent**
Nagao et al.

(10) Patent No.: **US D488,819 S**
(45) Date of Patent: **** Apr. 20, 2004**

(54) **DIGITAL CATV TERMINAL**

(75) Inventors: **Takayasu Nagao, Osaka (JP); Seigo Takahashi, Takatsuki (JP)**

(73) Assignee: **Matsushita Electric Industrial Co., Ltd., Osaka (JP)**

(**) Term: **14 Years**

(21) Appl. No.: **29/182,474**

(22) Filed: **May 27, 2003**

(30) **Foreign Application Priority Data**

Nov. 28, 2002 (JP) 2002-032896

(51) LOC (7) Cl. **14-03**

(52) U.S. Cl. **D14/496; D14/125**

(57) **CLAIM**

The ornamental design for a digital CATV terminal, as shown and described.

DESCRIPTION

FIG. 1 is a top perspective view of a digital CATV terminal of the present invention;

FIG. 2 is a front view thereof;

FIG. 3 is a rear view thereof;

FIG. 4 is a first side view thereof;

FIG. 5 is a second side view thereof;

FIG. 6 is a bottom view thereof; and,

FIG. 7 is a top view thereof.

1 Claim, 7 Drawing Sheets
